WORD FORMING GAME BOARD

Ethel Germain, New York, N.Y.

Application June 23, 1958, Serial No. 51,490

Term of patent 3½ years

(Cl. D25—1)

Fig. 1 is a plan view of a word forming game board showing my new design; and

Fig. 2 is a cross-sectional view taken through line 2—2 of Fig. 1.

The broken lines showing are for illustrative purposes only.

I claim:

The ornamental design for word forming game board, substantially as shown and described.
